UNITED STATES PATENT OFFICE.

LAWRENCE F. DONNELLY, OF LANSFORD, PENNSYLVANIA.

GOOGLES.

1,105,630.

Specification of Letters Patent.

Patented Aug. 4, 1914.

Application filed September 3, 1913. Serial No. 787,828.

To all whom it may concern:

Be it known that I, LAWRENCE F. DONNELLY, a citizen of the United States, residing at Lansford, in the county of Carbon and State of Pennsylvania, have invented certain new and useful Improvements in Goggles, of which the following is a specification.

My invention relates to improvements in goggles, and more particularly to eye protectors for use by miners and other workmen to protect the eyes from flying particles which would injure the eye.

A further object is to provide an improved protector of the character stated which permits of free ventilation so as to render the device comfortable to the wearer and construct the device so that it cannot be broken in ordinary use by fragments and particles flying in the air.

With these and other objects in view, the invention consists in certain novel features of construction and combinations and arrangements of parts as will be more fully hereinafter described and pointed out in the claims.

In the accompanying drawings: Figure 1 is a view in elevation illustrating my improvements in operative position, Fig. 2 is an enlarged front elevation of the goggles, and Fig. 3 is a view in cross section on the line 3—3 of Fig. 2.

My improved goggle comprises two plates 1, 1, having a hinged juncture 2 at their meeting ends, and said plates covered at their edges with felt or lamb's wool 3 secured in any approved manner, and offering a soft contacting surface against the face of the wearer, and insuring a tight juncture 40 with the face, so that particles cannot work their way into the eyes from under the plates.

The ends of the plate 1 are connected by a suitable band 4 which may be of elastic, and which is positioned around the head of the user to hold the goggles in place. Each plate 1 is provided with an elliptical forwardly projecting extension 5 which is open and constitutes a chamber located over the eye of the user. Each of these extensions 5 are covered at their outer ends by wire gauze 6, the edges of said wire gauze being bent over the extensions and confined within elliptical bands 7 forced over the end of the extension and effectually binding the gauze,

yet permitting the latter to be removed and replaced if desired.

The sides of the extension 5 are preferably perforated as shown at 9, so that there may be a free circulation of air through the extensions or chambers, not only through the gauze 6 but also through the openings 9, so that perspiration cannot form to interfere with the vision or the comfort of the user.

By providing the wire gauze 6, if a particle strikes the same, it cannot break the gauze as would be the case if glass were used, and furthermore, the air may freely circulate through the gauze which would not be true of glass or other similar transparent material. Furthermore, if the gauze becomes injured or the mesh clogged by reason of dirt which cannot be readily removed, the old gauze may be removed and replaced by a new gauze, the elliptical band 7 permitting such renewal.

Various slight changes might be made in the general form and arrangement of parts described without departing from my invention, and hence I do consider myself at liberty to make such changes and alterations as fairly fall within the spirit and scope of the appended claims.

Having thus described my invention, what I claim as new and desire to secure by Letters Patent is:

1. A device of the character described, comprising two plates hinged together, a soft binding around the edges of said plates, 90 said plates having elliptical open extensions, wire gauze located against the outer ends of said extensions, and elliptical bands fitting over the extensions and the edges of the gauze binding the latter against the outer 95 ends of the extensions, substantially as described.

2. A device of the character described, comprising two plates hinged together, a soft binding around the edges of said plates, 100 said plates having elliptical open extensions, wire gauze located against the outer ends of said extensions, elliptical bands fitting over the extensions and the edges of the gauze binding the latter against the outer ends of 105 the extensions, and said extensions having perforations in their walls, substantially as described.

3. A pair of goggles comprising two metal plates having hinge connection at their in- 110

ner ends, said plates adapted to be positioned over and cover the eyes of the user, a soft binding throughout the outer edges of both plates adapted to fit against the face of the user throughout the length of the goggles, said plates having elliptical openings with elliptical open forwardly projecting extensions, bands fitting around the ends of said extensions, and a netting of wire gauze 10 clamped between the forward ends of the

extensions and the bands, substantially as described.

In testimony whereof I have signed my name to this specification in the presence of two subscribing witnesses.

LAWRENCE F. DONNELLY.
